DISPLAY DEVICE

Frank Parr and Elmer Parr,
Mountain Lake, Minn.

Application December 27, 1941, Serial No. 424,591

2 Claims. (Cl. 40—36)

This invention relates to display devices and more particularly to devices of this kind, wherein a series of cards are changed, one after the other, to give a succession of data, such for example as a succession of advertising matter or a series of dates as in a calendar.

The device herein disclosed is shown specifically as a calendar, which is controlled by an electric clock, to change the cards once every twenty-four hours, but it is understood, of course, that this device may be used for any display matter, whatsoever, that is to be changed from time to time.

An electrically operated clock is shown only in diagram as the construction of this disclosure will be made the subject matter of a separate application for patent.

One object of this invention is to provide a calendar device having a magazine to receive a stack of cards, one for each day of the year, and a solenoid device to change them individually each twenty-four hours.

Another object is to provide, in a device of this kind means for ejecting, from the device, each card as it is being replaced.

Another feature is the method of advancing the cards in the magazine of the device.

Another feature is the solenoid actuated mechanism to remove the cards from the magazine ad seriatim.

Another object of this invention is to provide a device to feed a series of cards, having advertising matter printed thereon and which cards may be changed from time to time either manually by closing an electric contact or automatically by any well known electrical timing device, such for example, as an electrically driven synchronous clock which closes a circuit to the device at predetermined periodic intervals.

Additional objects and features of this invention will be brought out in the following description all of which come within the scope of the same.

Referring to the drawing:

Fig. 1 is a front view of the calendar device showing how an electric clock, to operate it, may be mounted on a common base with the calendar.

Fig. 2 is a sectional view of the device showing a solenoid mechanism for operating the same.

Fig. 3 is a diagram of electrical connections.

The same numerals are used throughout the different views for the same parts.

The calendar consists of a casing 1 within which is assembled the mechanism to accomplish the above results. In the upper part of the

casing 1 is mounted a rectangular receptacle 2 to receive a stack of printed cards 3 which are arranged in order to be displayed one after the other in succession. Each card may be printed for use as a calendar with the day of the week, the month and the day of the month as shown in Fig. 1. The card receptacle 2 has a rectangular cross section and is assembled in the casing 1 on an incline so that a stack of cards 3 inserted therein will tend to slide down towards the front of the casing 1, by the force of gravity with the assistance of a roller 4, inserted in the receptacle 2 and which bears against the back of the stack of cards 3. The cards are pressed against a display window pane 5 recessed in the front of the casing 1. The casing 1 has an opening 6, registering with the pane 5, so that the first card of the stack may be viewed therethrough. As the cards 3 are advanced in the receptacle 15 they enter successively one by one into a rectangular opening in a slide 7. Secured to the lower end of the slide 7 is one end of a cord or cable 8 which passes under a grooved pulley 9 pivoted to a bracket 10 secured to the casing 1. The opposite end of the cable 8 is then secured to the lower end of a lever 11 pivoted at 12 to a horizontal cross bracket 18 secured at each end to the casing 1. The upper end 13 of the lever 11 is pivoted at 14 to the outer end of a movable iron solenoid core 15, slotted at 16 to receive the same. A stop 17, secured to the casing 1, limits the outward movement of the core 15. The upper end of the slide 7 has one end of a cable 19 secured to it, which passes over a grooved pulley 20 and is secured at its opposite end to one end of a spiral spring 21, having its other end hooked into the end of a screw 22 in the casing 1.

In order to control the movements of the core 15 electrically, its end is slidably mounted in one end of a tube 25 having a flange 23 at each end thereof, and insulated wire 24 wound on the tube 25. The opposite end of the tube 25 is provided with a short stationary iron core 30 secured by screw 29 to a bracket 26, secured by screws 28, to a flange 27 of the cross bar 18. It is readily seen that as current is passed through the solenoid windings the core 15 is drawn into the tube 25 thereby moving the slide 7 downwardly against the tension of the spring 21. As this movement takes place the first card 3 in the stack is moved downwardly from the opening 6 to a lower opening 31 in the casing 1 through which it is ejected by a spring 32, secured at its lower end to the flange 27 of the cross bar 18, and free at its

upper end to press against the rear of the first card, as it is moved downwardly, to eject it. When the solenoid is de-energized, the spring 21 will return the slide 1 to its normal upper position shown in Fig. 2, and permit the next card 3 to enter the opening therein, and so forth until all the cards have been advanced and ejected, at which time a new stack of cards may be inserted in the receptacle. Back of the slide 1 is a guide plate 33 secured to the forward end of the receptacle 2 by screws 34. The slide 1 moves between the guide plate 33 and the inside of the front of the casing 1.

The diagram in Fig. 3 shows the line wires 35 connected to a clock motor 36, also to the solenoid windings 24, which may be connected in the circuit 35 manually by a push button or switch 37 and also automatically by the contacts 38, actuated by the clock motor 36, to close the circuit 35. A main line switch 39 to the solenoid windings 24 is provided to cut out the operation of the device if desired but without disturbing the operation of the clock itself.

The clock 40 shown in Fig. 1 may be of any type that will make an electric contact at pre-determined periodic intervals.

Having described our invention so that anyone skilled in the art to which it pertains can make and use the same, what we claim as our invention and wish to secure by Letters Patent is:

1. A card display device including a casing, having an observation opening in the front member thereof, to display the first of a stack of movable cards therein, an inclined receptacle for

the cards, mounted in said casing, and terminating at one end of said opening, a weight in the receptacle effective to advance the cards as a group towards the opening, a slide member, mounted to slide on the surface of the front member, and having an aperture therein, to receive the first card of the stack and holding the same in front of said observation opening, a solenoid device to actuate the slide member, whereby the first card is removed from observation, including a cable secured to the slide member at its lower end and a lever connecting the cable to said solenoid device.

2. A card display device including a casing, having an observation opening and a card outlet in the front member thereof, to display the first of a stack of movable cards therein, an inclined receptacle for the cards, mounted in said casing, and terminating at one end of said opening, a weight in the receptacle to bear against and advance the cards as a group towards the opening, a slide member, mounted to slide on the inside surface of the front member, and having an aperture therein to receive the first card of the stack and holding the same in front of said observation opening, means to move the slide member from its initial position to a lower position, whereby the first card is removed from observation, means to return the slide member to its initial position, and means to eject a card through said outlet when the slide member is in its lower position.
